DIGITAL CLOCK RADIO

Benito Mishiro, Sakai-shi, Osaka, Japan, assignor to
Matsushita Electric Industrial Co., Ltd., Kadoma-shi,
Osaka, Japan

Filed Apr. 17, 1974, Ser. No. 461,767

Claims priority, application Japan Oct. 22, 1973

Term of patent 14 years

Int. Cl. D14—03

U.S. Cl. D56—4 B

FIG. 1

FIG. 2

FIG. 1 is a front, top and right side perspective view of a digital clock radio showing my new design; and

FIG. 2 is a rear, bottom and left side perspective view.

Portions of the drawings are shaded to indicate contrast in appearance, and portions are diagonally inclined to indicate transparency. The channel selection indicator and the framing thereof, partially obscured by the right side wall, are symmetrical, and the distance between said wall and the right side of said framing is approximately the same as that between the left side wall and the outer frames around the alarm setting indicator and the digital readout.

I claim:

The ornamental design for a digital clock radio, as shown and described.
